UNITED STATES PATENT OFFICE

GEORGE ANDERSON AND VICTOR A. GRONBERG, OF JAMESTOWN, NEW YORK, ASSIGNEES
TO ART METAL CONSTRUCTION COMPANY, OF JAMESTOWN, NEW YORK

LOCKING MECHANISM FOR DRAWERS

Application filed January 9, 1926. Serial No. 80,314.

This invention relates to locking mechanisms for the movable drawers or elements of desks and analogous articles of furniture, in which a plurality of movable drawers or 5 elements to be locked are disposed, for example, in different vertical tiers or in laterally different positions, the mechanism being of that character in which, by the actuation of a single operating bar or other member, all 10 or several of the drawers or elements are locked and all are released, so that they may be opened or moved by unlocking a single lock.

Locking mechanisms of various different 15 constructions for such purposes have been proposed, and many different mechanisms have been made and used, but the locking mechanisms as heretofore designed for the purpose are not entirely satisfactory from 20 one standpoint or another. While some of these previous mechanisms have more or less successfully accomplished the intended purpose, they are complicated and composed of many parts which are difficult or troublesome 25 to assemble, thus unduly increasing the cost of the mechanisms. Some of the previous constructions, while operating to securely lock the movable drawers or members, are so designed that they do not operate freely and 30 smoothly, and considerable effort is required to actuate the mechanisms to lock and release the drawers, thus making them objectionable from a practical standpoint.

One of the principal objects of this invention 35 is to produce a mechanism for locking drawers or other movable elements disposed in different vertical tiers, at different elevations, or different lateral or other dispositions, which is of simple and comparatively 40 inexpensive construction and composed of the minimum number of parts, which can be readily made, assembled and installed in the desk or other article, and which at the same time will insure ease of operation of the 45 mechanism for locking and releasing the drawers or elements. Other objects of the invention are to design the mechanism so that it is more or less flexible and adapted to be readily modified as may be necessary to 50 suit different arrangements or dispositions of

the drawers or elements, and also to improve locking mechanisms of the sort mentioned in the other respects hereinafter described and set forth in the claims.

In the accompanying drawings, the locking 55 mechanism is shown as applied to a desk of that type which is provided with drawers in vertical tiers in the pedestals at opposite ends of the desk, and also with a movable typewriter cover or top section between the desk 60 pedestals for moving a typewriter or analogous machine to and from an operative position and enclosing and protecting the same when not in use. The invention is also illustrated in connection with a roll top desk in 65 which the curtain is employed as the actuating member for the locking mechanism. It will be apparent, however, that the locking mechanism is such that with but slight and obvious modifications it can be readily 70 adapted for desks having drawers in one or more pedestals and also over the knee space between the pedestals, or other dispositions of the drawers or elements, and for analogous articles having a plurality of movable draw- 75 ers or elements requiring to be locked.

In said drawings:

Fig. 1 is a front elevation on a reduced scale, of a typewriter desk provided with locking mechanism embodying the invention. 80

Fig. 2 is a central, sectional elevation thereof.

Fig. 3 is a sectional plan view on an enlarged scale on line 3—3, Fig. 1.

Fig. 4 is a longitudinal, sectional elevation 85 thereof on line 4—4, Fig. 3.

Fig. 5 is a fragmentary, sectional plan showing the mechanism adapted for locking a central drawer between the pedestals.

Figs. 6 and 7 are similar enlarged, trans- 90 verse, sectional elevations of the locking mechanism on line 6—6, Fig. 3, showing respectively the locked and released position of the parts.

Fig. 8 is a longitudinal, sectional elevation 95 thereof on line 8—8, Fig. 7.

Fig. 9 is a fragmentary section similar to Fig. 6, showing the locking bolt for the typewriter cover in position about to lock the cover. 100

Fig. 10 is an enlarged, transverse, sectional elevation of the locking mechanism on line 10—10, Fig. 3.

Fig. 11 is a similar section thereof on line 11—11, Fig. 12.

Fig. 12 is a sectional elevation on line 12—12, Fig. 10.

Fig. 13 is a sectional elevation on line 13—13, Fig. 12.

Fig. 14 is an enlarged, sectional detail of the locking mechanism on line 14—14, Fig. 6.

Fig. 15 is a fragmentary, sectional elevation showing a modification in which one of the drawers is utilized as the operating member for actuating the mechanism to lock the remaining drawers.

Fig. 16 is a fragmentary, sectional plan view of the lower portion of a roll top desk illustrating the use of the roll curtain for actuating the drawer-locking mechanism.

Fig. 17 is a fragmentary, longitudinal, sectional elevation thereof on line 17—17, Fig. 16, showing the parts in unlocked position.

Fig. 18 is a similar figure showing the parts in locked position.

A metal desk is shown in the drawings having pedestals *a*, *b* at opposite ends separated by a knee space *c* adapted to house a typewriter or other machine. Three drawers *d* are shown in a vertical tier in the left hand pedestal *a* and two drawers *d'*, one above the other, are shown in the right hand pedestal, while in the space between the pedestals is shown a movable support *e* for a typewriting or other machine, and a cover *f* which is adapted to move to and from the horizontal position shown in Figs. 1 and 2, in which it forms the middle section of the desk top and overlies the machine support *e*. The cover *f* is movable rearwardly and downwardly into the desk for uncovering and raising the support *e* with the machine thereon to position for operating the machine, the cover being connected to the machine support *e* by usual means, not shown, whereby the machine support is actuated by the movement of the cover *f*. The several drawers *d* in the two pedestals and the cover or top section *f* between the pedestals are all adapted to be locked by the locking mechanism hereinafter described.

20 represents a horizontal rock shaft which extends in a direction from end to end of the desk, or transversely thereof and of the vertical planes in which the drawers or elements to be locked move. This shaft is connected by a rock arm 21 to a push rod 22 which extends forwardly from the rock shaft with its front end or extremity projecting through 60 and guided in an opening in the front of the desk so that the rod can be pushed inwardly to oscillate the rock shaft. The rock shaft is also connected by rock arms 24 to vertical keeper or locking bars 25. Preferably, the 65 rock arms are pivoted directly to the push

rod and locking bars. A suitable spring, preferably a spring wire 23, coiled about the rock shaft with its ends hooked over the arm 21 and the shaft bearing 26, tends to lower the locking bars and move the push rod forwardly. There is one of these vertical locking bars for each vertical tier of drawers, each bar being arranged in rear of or adjacent to a tier of drawers so as to engage latches connected to the several drawers in the tier. Two locking bars 25 are shown, one for the drawers in each pedestal of the desk, but it will be manifest that if more than two tiers of drawers or elements to be locked are employed, it is only necessary to add an additional bar 25 with its connected rock arm for each additional tier of elements, and further, that the rock shaft is adapted to be similarly equipped with a rock arm and latch-engaging member for one or more drawers or elements arranged between the pedestals.

The rock shaft 20 is preferably journaled in bearing brackets 26, which as shown, consist of angle-shaped metal plates welded or otherwise suitably secured to the vertical, inner side walls 27 of the pedestals. Supplemental angle-shaped, metal bearing plates 28 are welded or otherwise rigidly secured to the bearing brackets 26, and are provided with holes in which the extremities of the rock shaft bear and are adapted to turn. Each of the rock arms 21 and 24 preferably consists of a metal stamping and is secured to the rock shaft as shown in Figs. 10 to 12, by slotting the arm at 29 so as to straddle the shaft with the edges of the slot 29 fitting in a pair of narrow, transverse saw kerfs or slots 30 formed in opposite sides of the shaft. The slots in the arm and shaft are made so as to cause a tight fit of the shaft in the slot 29 and of the bifurcated portion of the arm in the saw kerfs. The parts have a driving fit or, if desired, the parts can be pinched or upset slightly so as to prevent disengagement of the arm from the shaft. This manner of attaching the rock arms to the shaft provides a very simple and inexpensive connection between the parts, which is nevertheless very rigid and secure and prevents the arms from turning or shifting axially on the shaft.

As shown, the rock arms 24 for the locking bars are located close to the inner faces of the supplemental bearing plates 28, and the rock arm 21 is located at the outer face of the vertical portion of the bearing bracket 26 so that the rock arms thus serve to prevent axial shifting or displacement of the rock shaft in its bearings.

Each of the vertical locking bars 25, which are preferably angle bars, extends through and is adapted to slide vertically in guide holes 31 in the horizontal portion of one of the bearing brackets 26, and in a vertical bracket 32 welded or otherwise suitably secured to the inner pedestal wall at the lower

portion of the locking bar, see Fig. 4. A latch or catch 33, see Figs. 4 and 10, is attached to each of the drawers and is adapted to interlock with a portion of the locking bar for locking the drawer. As shown, each latch is pivoted to a flanged bar 34 fixed to and extending rearwardly from one of the drawers, and the latch is adapted to enter a hole 35 in the front flange of the locking bar, the latch having in its underside a notch 36 adapted to engage the lower edge of the hole 35 to lock the drawer. Preferably, the latch is held yieldingly down against the lower flange of the bar 34 by a spring 37 secured in a hole in the latch pivot and having a bent end hooked over the free end of the latch. Figs. 3 and 4 show the unlatched or released position of the parts, and Figs. 10 and 13 show respectively by full and broken lines, the released and locked position of the parts. It will thus be seen that when the operating push rod 22 is in the forward position shown, with its front end projecting outwardly from the front face of the disk, the locking bars will be in their lowermost position, and the latches 33 are adapted to move freely horizontally into and out of the holes 35 in the locking bars. When the drawers are closed, the notches 36 in the latches will be in the vertical plane of the slotted front flange of the locking bars, and if the push rod 22 is then shoved inwardly, the locking bars will be lifted, thereby interlocking the edges of the holes of the locking bars with the notched latches and thus securing or locking the drawers. The rear ends of the latches are bevelled, as shown, and if a drawer should be pushed in or closed when the locking bar for the same is in its upper locking position, the latch of said drawer will ride upwardly over the lower edge of its hole 35 and the latch spring will throw the latch into holding engagement with the locking bar when the drawer is fully closed, so that the drawers will always be locked when moved inwardly to their closed position, notwithstanding that the locking bars or locking mechanism may have been previously moved to locking position.

In the case of a desk which has a central drawer instead of the typewriter cover *f* over the knee space or between the pedestals, represented in Fig. 5, in which *g* indicates the drawer, then another rock arm 24^a, Fig. 5, similar to the rock arms 24, is secured to the rock shaft 20 between the pedestals, and a locking member 25^a attached to the arm is adapted to engage a latch 33 carried by the drawer *g* for locking the latter. When there is only one central drawer *g* which is usually the case, a vertical locking bar, such as the bars 25, is not necessary, and the locking member 25^a can be formed by a simple cross piece fixed to the arm 24^a, as shown in Fig. 5. It will be apparent, how-

ever, that a central tier of drawers between the pedestals could be locked simply by connecting another locking bar 25 to the rock arm 24^a, for engagement with latches carried by each of the several drawers of the central tier. As shown in Fig. 3, the rock shaft 20 is provided with notches 30 for the attachment of the arm 24^a, so that the arm 24^a can be used when the mechanism is to be applied to a desk having a central drawer, or omitted when the mechanism is used on desks having no central drawer. In like manner, the mechanism can be readily adapted for desks in which the drawers are differently located, simply by providing the rock arms and locking bars or members at appropriate points along the rock shaft 20.

For a desk having a movable typewriter cover or top section *f*, which is the type shown in the drawings except in Fig. 5, a spring actuated bolt or latch 40 is preferably provided, arranged at one side of the front end of the cover *f* for locking the cover in closed position. As shown, the bolt is adapted to enter a slot 41 in the adjacent vertical edge of the cover *f*. This bolt is preferably slidably mounted in the inner, front pedestal leg of the desk just above the front portion of the push rod 22 and at right angles thereto. Both the push rod 22, which operates the locking mechanism for the pedestal drawers, and the bolt 40 for locking the cover *f* are locked or secured in locking position by the same lock-controlling mechanism, which, in the preferred construction, will now be described, see particularly Figs. 6-9.

43 represents a key actuated lock of any desired type, such for instance as a Yale barrel lock. This lock is secured to the horizontal bottom of a metal support or frame 44 which is stationarily secured by means, not shown, in the front pedestal leg, with the front end of the lock, in which the keyhole is located, exposed through a hole 45 in the front wall of the leg, so as to permit the insertion of the key into the keyhole. The lock is provided at its rear end with a cam or arm 46 which is oscillated by turning the key in the lock. This cam 46 engages a forwardly projecting lug on a vertical locking plate 47 arranged to slide vertically against the vertical back of the support 44. This locking plate is guided by a tongue or projection 48 at its lower end passing through a guide hole in the bottom of the support 44 and by a lug 49 projecting inwardly from the upper portion of a side vertical flange of the support 44. The locking plate 47 has an opening 50 through which the push rod 22 passes and the latter has in its upper edge a notch 51 in which the upper edge of the hole 50 is adapted to drop when the push rod is in its inward locking position. The plate is pressed downwardly by a suitable spring 52 carried by the support 44 and engaging a lug 49^a of

the locking plate, and the plate is adapted to be lifted against the action of this spring by the key-operated cam 46 which bears against this lug, as shown in Fig. 17. When the push rod 22 is in its forward position, that is the drawer-releasing position, the locking plate 47 will be held elevated by engagement of the upper edge of its slot 50 with the top edge of the push rod. When the push rod is moved inwardly for locking the drawers, the locking plate 47 will be lowered by its spring 52 with the upper edge of the slot 50 engaging in the slot 51 in the push rod, thereby locking the latter, and the drawer-locking parts connected therewith.

The bolt 40 for the cover *f* is also retracted to release the cover through the medium of this same locking plate 47. For this purpose, a lever 53 is pivoted on a stud 54 projecting forwardly from the back of the support 44 through an elongated slot in the plate 47. A stud 55 fixed to the plate 47 extends into a slot 56 in the lever 53, and the upper portion of the lever is provided with an opening 57 into which projects a stud 58 on the bolt 40, so that when the locking plate 47 is raised by the key-actuated lock, the upper end of the lever 53 swings inwardly and draws the bolt 40 inwardly to release the cover *f*. A suitable spring 59, engaging the stud 58 moves the bolt 40 to locking position when this is permitted by the downward movement of the locking plate 47. The bolt 40 has a bevelled upper edge, so that if the cover *f* is closed when the bolt 40 is projected, or in its locking position, the bolt will be forced back by the cover and will then be thrust into locking engagement with the cover by its spring 59. The opening 57 in the lever is shaped to permit this movement of the bolt independently of the lever and the locking plate 47 when the latter are in locked position, so that the cover can be closed and locked without requiring the actuation of the lock by means of the key.

The locking mechanism herein described is simple and composed of few parts of simple construction, adapted to be readily and quickly made and assembled, and the construction is such that the mechanism can be operated with ease to lock the drawers, simply by pushing inwardly on the front end of the push rod 22 and to release or unlock the drawers by inserting and turning the key in the lock 43. The push rod is directly pivoted to an arm on the rock shaft 20, which in turn is pivotally connected by rock arms with the vertical keeper or locking bars 25, so that very little effort is required to move the push rod inwardly to rock the shaft and raise the locking bars to lock the drawers, and inasmuch as the weight of the vertically movable locking bars supplemented by the light spring 23 tends to move the parts to releasing position, very little effort is required to unlock the drawers, and

the key can be easily turned for this purpose. As thus indicated, the mechanism can be operated with ease both to lock and release the drawers, and nevertheless the construction is such that proper locking of the drawers or elements is insured, and the simplicity of the mechanism and the direct connection of the parts insures that the mechanism will not readily get out of order.

The push rod 22 can be omitted, and if desired, one of the drawers utilized in its stead to operate the mechanism to lock the drawers. This can be done, as shown in Fig. 15, simply by fixing to one of the drawers, for instance, the top drawer in the right hand pedestal, a rearwardly projecting bar or member 60 having a cam or bevelled end adapted, when the drawer is shoved into its closed position to enter a slot in the companion locking bar 25 and lift the bar to locking position. In such case, the drawer which operates the locking bar is provided with a lock of any suitable kind for locking it when shut. This drawer must be unlocked to open it, and the opening of the drawer permits the locking mechanism to act as when the push rod 22 is released, to unlock the other drawers.

The invention is illustrated in Figs. 16 to 18 as applied to a roll top desk, in which construction the roll curtain is used to actuate the locking members 25 and rock shaft 20. For this purpose, one of the locking members 25 (the right hand one in Fig. 16) is provided with a rearwardly extending bracket arm 62 secured thereto, and which is adapted to project into the path of the back edge portion 63 of the roll curtain. When the curtain is moved to its open position, its rear edge 63 passes downwardly in guides (not shown) in rear of the drawers 64 in the pedestals *a* *b* of the desk (portions only of which are shown), engaging the bracket 62 and depressing the adjacent locking member 25, see Fig. 17, so as to disconnect the same from the drawer latches 33 and permit the drawers to be withdrawn. When, however, the rear edge 63 of the roll curtain moves upwardly away from the bracket 62 in the closing movement of the curtain, a tension spring 65 connected to the bracket 62, or other part of the locking member, and to a fixed part of the desk, such as the bracket or plate 26, pulls the locking member upwardly into locking engagement with the latches 33 and prevents the drawer from being withdrawn. Thus, it will be seen that the curtain 63 constitutes the operating member for actuating one locking member 25 by engaging the bracket 62, and through this member 25, rocks the shaft 20, thus actuating the other locking member 25 in the left hand pedestal. The desk, of course, is provided with the usual lock for locking the curtain when in its closed position, at which time

all the drawers are locked by the locking mechanism, as in the other constructions. If desired, all of the locking members could be provided with bracket arms 62 for direct actuation of these members by the roll curtain.

We claim as our invention:—

1. In a locking mechanism, the combination of a rock shaft, means for rocking the same, a rock arm secured to said shaft, and a locking member actuated by said rock arm, said arm having a bifurcated portion straddling said shaft and having a driving fit in opposed transverse segmental slots in said shaft whereby said rock arm is rigidly secured to said shaft and prevented from turning or endwise movement relative to said shaft.

2. In a locking mechanism, the combination of a rock shaft, a locking member actuated thereby, means for rocking said shaft including a rock arm secured to said shaft, said arm having a bifurcated portion forming a slot with parallel inner side edges, and which straddles said shaft and fits in opposed transverse segmental slots in said shaft, said slots having parallel bottom walls against which said slot walls bear tightly whereby said rock arm is rigidly secured to said shaft and prevented from turning or endwise movement relative to said shaft without the use of fastening devices.

3. The combination with a plurality of drawers or elements to be locked arranged to move in different vertical planes disposed laterally relatively to each other, of locking mechanism therefor comprising a horizontal rock shaft extending transversely of said vertical planes, a vertically movable locking member actuated by said rock shaft for locking one of said elements, a push rod for rocking said shaft, a transverse horizontally slidable locking bolt for another element arranged adjacent to and transversely of said push rod, a lock for said push rod, and mechanism controlled by said lock for releasing both said push rod and said bolt.

4. The combination with a plurality of drawers or elements to be locked, of locking mechanism for one of said elements including an operating push rod, a transversely movable sliding locking bolt for another element arranged adjacent to said push rod to move transversely thereof, a vertically movable locking plate arranged parallel with said bolt to engage said push rod to lock the same, a vertically swinging plate to release said push rod, and means also actuated by said lock for releasing said bolt.

5. A plurality of elements arranged in a vertical tier, and locking mechanism for said elements including a rock shaft, latches on said elements, a vertical locking bar operatively connected to said rock shaft and which is movable up and down to engage or release said latches by rocking said shaft in opposite

directions, and an operating push rod for rocking said shaft in combination with another element disposed laterally relatively to said tier of elements, a transverse, sliding lock bolt for said other element located adjacent said push rod, and a lock controlled mechanism which locks said push rod and is actuated by the operation of said lock to release said push rod and move said bolt to release said other element.

6. The combination with an element to be locked, and locking mechanism therefor, including an operating push rod, and a lock for locking said push rod to hold said locking mechanism in locking position, of a second element, a transverse horizontally sliding locking bolt for the same arranged adjacent said push rod and which is adapted to enter an opening in said element and is actuated by said lock to release said element when said lock is operated to release said push rod.

7. The combination with a plurality of elements to be locked, of locking mechanism for one of said elements including an operating push rod, a lock, a locking bolt for another element arranged adjacent to said push rod to move transversely thereof, a locking plate arranged parallel with said bolt to engage said push rod to lock the same, an arm on said lock engageable with said locking plate to release said push rod, and means also actuated by said arm for releasing said bolt.

8. The combination with a plurality of elements to be locked, of locking mechanism for one of said elements including an operating push rod, a lock, a locking bolt for another element arranged adjacent to said push rod to move transversely thereof, a locking plate arranged parallel with said bolt to engage said push rod to lock the same, an arm connected with said lock to swing against said locking plate to release said push rod when said lock is operated, and a pivoted lever also actuated by movement of said arm to retract said bolt to release said other element.

9. The combination with a plurality of elements to be locked, of locking mechanism for one of said elements including an operating push rod, a lock, a locking bolt for another element arranged adjacent to said push rod to move transversely thereof, a locking plate arranged parallel with said bolt to engage said push rod to lock the same, means for yieldingly holding said locking plate in locking position, an arm on said lock engageable with said plate to move the same against the action of said yielding holding means to release said push rod, and means also actuated by said arm for releasing said bolt.

10. The combination with a plurality of elements to be locked, of locking mechanism for one of said elements including an operating push rod, a lock, a locking bolt for another element arranged adjacent to said push rod to move transversely thereof, a locking

plate arranged parallel with said bolt to engage said push rod to lock the same, means for yieldingly holding said locking plate in locking position, an arm on said lock engageable with said plate to move the same against the action of said yielding holding means to release said push rod, a pivoted member engageable with said bolt, means for yieldingly holding said bolt in locking position, and said bolt being also movable to a position to release said other element against the action of said last mentioned yielding means by the movement of said arm.

11. The combination with a plurality of elements to be locked arranged in different vertical tiers disposed laterally relatively to each other, of locking mechanism therefor comprising a rock shaft extending transversely of and in rear of said tiers of elements, said shaft having a plurality of spaced pairs of notches formed therein, a rock arm fixed on said shaft for each different tier of elements, said rock arms each having a bifurcated part adapted to fit in one of said pairs of notches in said rock shaft, whereby said arms can be positioned at different points on said shaft in accordance with the spacings of different sets of tiers, a locking member connected to each of said rock arms, a latch connected to each of said elements and arranged to cooperate with one of said locking members for locking said elements, said latches being engaged and released respectively by upward and downward movements of said locking members, an operating member for rocking said rock shaft to lock said elements, and a lock for said operating member.

12. A locking mechanism including a rock shaft and a rock arm, said shaft having transverse opposed segmental slots therein and said arm having a bifurcated portion which straddles said rock shaft and fits tightly in said slots so as to prevent turning and endwise movements of said arm relatively to said shaft, and the interfitting of said interengaging parts of said arm and shaft also preventing the disconnection of said arm from said shaft.

GEORGE ANDERSON.
